SHOWER STALL

Morison Stuart Cousins, 74 Victor St., Plainview, N.Y.
11803, and Michael Alan Cousins, 8 Jayne Ave., Huntington, N.Y. 11743

Filed Apr. 21, 1972, Ser. No. 246,507

Term of patent 14 years

Int. Cl. D23—02

U.S. Cl. D23—57

FIG. 1

FIG. 2

FIG. 3

FIG. 4

FIG. 1 is a perspective view of a shower stall showing our new design;

FIG. 2 is an enlarged cross-sectional view taken on line 2—2 of FIG. 1;

FIG. 3 is an enlarged cross-sectional view taken on line 3—3 of FIG. 1; and

FIG. 4 is an enlarged cross-sectional view taken on line 4—4 of FIG. 1.

The broken line representation of shower fittings in the four views is for purposes of illustration only.

What is claimed is:

The ornamental design for a shower stall, substantially as shown and described.
